UNITED STATES PATENT OFFICE.

PIERRE LECOMTE DU NOÜY, OF NEW YORK, N. Y.

DEVICE FOR MOVING FLUIDS.

1,335,672.

Specification of Letters Patent. Patented Mar. 30, 1920.

Application filed April 22, 1919. Serial No. 291,847.

To all whom it may concern:

Be it known that I, PIERRE LECOMTE DU NOÜY, a citizen of France, and a resident of the city of New York, borough of Manhattan, in the county and State of New York, have invented a new and Improved Device for Moving Fluids, of which the following is a full, clear, and exact description.

The present invention relates to new and useful improvements in devices for moving fluids, and pertains more particularly to apparatus for use in transferring fluids in surgical operations and other cases requiring cleanliness, sterility and absence of moving or corroding parts.

In devices of this character, it is desirable that a continuous flow of the fluid be maintained, and it is an object of the present invention to enable this result to be obtained.

It is a further object of this invention to construct a device in such a manner that the rapidity at which fluid is transferred may be varied at the will of the operator, and, at the same time, maintain a practically continuous flow, while at all times preventing back flow.

With the above and other objects in view, reference is had to the accompanying drawings, in which—

Figure 1 is a side elevation of the device, and

Fig. 2 is a vertical sectional view taken on the line 2—2 of Fig. 1.

Referring more particularly to the drawings, the device comprises a base 5, near one end of which is mounted a motor 6, preferably of the electric type. Power for this motor is supplied by means of the electric conductors 7, and its supply to the motor 6 is controlled by means of the switch 8. The reference character 9 designates a suitable housing, in which is mounted a transmission gearing, and said gearing is driven by means of a shaft 30, which in turn receives its power from the motor 6.

Mounted in bearings 11, is a shaft 10, said bearings being secured to the base 5 by means of bolts or the like 12. Splined to the shaft 10, by means of keys 13, are two spaced disks 14, and freely rotatable in said disks are rollers 15.

The reference character 16 designates a

pair of brackets in which is pivoted a member 18, the upper face of which is curved as at 19, the pivotal point of said pivoted member 18 being designated by the reference character 17. A dash-pot 20 is secured to the base and projecting upwardly of the dash-pot 20, is a stem or rod 21, the outer end of which is suitably secured to the under face of the pivoted member 18.

The reference character 22 designates a flexible tubing, and said flexible tubing is adapted to lie in contact with the curved upper face of the pivoted member 18, as best shown in Fig. 1.

The operation of the device is as follows: Upon operation of the motor, the transmission gearing in the housing 9 is driven through the medium of the shaft 30 and said transmission mechanism serves as the means for driving the shaft 10, which, however, forms no part of the present invention, and is not, therefore, herein shown. As the shaft 10 rotates, the rollers 15 successively engage the flexible tube 22 and press the same as shown in Fig. 2, in such a manner that any fluid which may be contained within said tube will be forced to travel therethrough. As the rollers 15 continue to move in contact with the flexible tube 22, it will be seen that a constant flow of liquid therethrough is maintained, the speed at which said liquid flows being determined by the speed of rotation of the several rollers 15.

From the foregoing description, it will be apparent that the present invention provides a device of the character described in which a constant flow of fluid may be maintained at a predetermined pressure, and, furthermore, by regulation of the speed of the motor 6, the rate of movement of the fluid through the flexible tube 22 may be varied.

Having thus described the invention, what I claim as new and desire to secure by Letters Patent is—

1. A device of the character described comprising a plurality of spaced disks, means for rotating said spaced disks, a plurality of rollers freely revoluble between said disks and carried thereby, a movable compressing surface, and a flexible tubular member adapted to be compressed against the

yieldable compressing surface individually by said plurality of rollers upon the rotation of the spaced disks.

2. A device of the character described comprising a pair of spaced disks, rollers carried by said disks in spaced relation to each other, a yieldingly mounted block hav-

ing a curved face arranged in spaced relation to said disk and rollers, and a flexible tubular member adapted to be compressed against the curved surface of said yieldingly mounted block individually by said spaced rollers upon rotation of said disks. 10

PIERRE LECOMTE DU NOÜY.
